UNITED STATES PATENT OFFICE.

ALBERT J. SLADE, JR., OF PEARL RIVER, NEW YORK, ASSIGNOR TO DEXTER FOLDER COMPANY, OF PEARL RIVER, NEW YORK, A CORPORATION OF NEW YORK.

PAPER-FEEDING MACHINE.

1,147,562.

Specification of Letters Patent.

Patented July 20, 1915.

Application filed March 23, 1914. Serial No. 826,639.

To all whom it may concern:

Be it known that I, ALBERT J. SLADE, Jr., a citizen of the United States, and a resident of Pearl River, county of Rockland, 5 and State of New York, have invented certain new and useful Improvements in Paper-Feeding Machines, of which the following is a full and clear specification.

This invention relates to paper feeding machines and more especially to that type of feeding machines constituting the subject matter of the application of Talbot C. Dexter, Ser. No. 795,486, filed October 16th, 1913.

15 The primary object of this invention is to provide an improved construction for automatically varying the pressure on the tail drag with a view to simplifying the operation of regulating the duration of the 20 sheet combing operation.

One of the main purposes of this invention is to provide means for varying the pressure on the tail drag, the construction and arrangement of parts being such that 25 whenever the pressure on the tail drag is automatically reduced for the purpose of facilitating the movement of a sheet into position beneath the drop rollers, the desired position of the sheet will be attained 30 before the end of a certain predetermined period of combing which is constant unless the arrival of the sheet into registry position automatically shortens such period by its actuation of suitable means for that 35 purpose. In this way a misfeed is practically eliminated and the pressure on the tail drag will be automatically brought to normal position after each combing operation, suitable means being provided for adjusting this normal pressure to any desired tension.

Other and further objects will appear in the specification and be pointed out in the appended claims, reference being had to the 45 drawings which exemplify my invention and in which—

Figure 1 is a side elevation of a portion of a sheet-feeding machine which embodies the improvements; Fig. 2 is a top plan view 50 of the same; Fig. 3 is a fragmentary detail elevation showing a modification of the pressure-varying throwout device. Fig. 4 is a fragmentary section on the line IV—IV, Fig. 2.

55 In the drawings which show the preferred

embodiment of my invention, the shaft 1 is journaled in suitable side frames 2 (only one being shown). Journaled upon the shaft 1 is a sleeve 3 upon which is mounted the hubs 4 of laterally spaced lever arms 5. 60 Journaled within the outer ends of the lever arms 5 is a shaft 6 to which is keyed the combing wheel 7. A cam arm 8 carries a roller 9 which travels on a cam 10 for periodically raising and lowering the combing 65 wheel 7. Said cam 10 is keyed to a shaft 11. This sheet feeding mechanism constitutes one of a pair which are spaced laterally of the machine, the regulation of the 70 periods of activity of which makes it possible to present the sheet in proper relation to the drop roller mechanism which feeds the same from the pile. Keyed to the shaft 1 are sprocket wheels 12 which transmit power by means of sprocket chains 13 to 75 the sprocket wheels 14 keyed to the spindles 6, these connections being adapted to continuously rotate the combing wheel 7 during their rising and falling movements which carry them to and from the pile of sheets P. 80 Suitable means may be provided for bringing about a proper register of the sheet by regulating the periods of activity of the combing wheel 7 for the purpose of advancing either edge of the sheet more or less 85 with respect to its other edge by the sheet-actuated means now to be described. Thus, a rock shaft 15 which is journaled within the side frames 2, has keyed thereto a segmental ratchet 16. Journaled upon the 90 shaft 15 and terminating adjacent to the segmental ratchet 16, is a sleeve 17 which carries a cam disk 18 adjacent to the segmental ratchet 16. Journaled within the cam disk 18 but not attached thereto and a 95 radially projecting finger 19 spaced laterally therefrom upon the sleeve 17, is a small shaft 20 which carries a pawl 21 which is adapted to engage the teeth of the segmental ratchet 16 when said pawl is displaced in 100 the manner to be presently explained. Depending from the shaft 20 is a pendulum 22 which is normally disposed in the path 105 of a sheet fed from the pile P, the displacement of said pendulum by a sheet being adapted to throw the pawl 21 into the teeth of ratchet 16. Whenever this occurs, the sleeve 17 is forced to partake of the movement of shaft 15 in one direction so that a cam roller 23 which is carried by cam arm 110

24 projecting from the sleeve 4 is caused to rise to the outer run of the cam 18, thus elevating the combing wheel 7 and terminating this period of activity upon the top sheet of a pile. This mechanism is fully described in the applications of George A. Martin, Serial Number 773,282, filed June 12th, 1913, and in the above mentioned application of Talbot C. Dexter, and need not be more fully referred to in this specification.

An oscillatory movement is imparted to the shaft 15 by means of a rock arm 25 which is pivotally connected to one end of a connecting link 26, the other end of said link being pivotally connected to a crank arm 27 of smaller length than the lever arm 25, said crank arm 27 being keyed to the shaft 11 and rotated thereby. It will be seen therefore, that each combing wheel is raised and lowered at regular periodic intervals by means of the combing roller 9, and if during the period while the combing wheel is upon the pile, the forward edge of the top sheet thereof reaches the pendulum 22, the engagement of the pawl 21 with the ratchet 16 will cause the elevation of the combing wheel 7 on that side prior to the time it would be raised by the periodic cam 10. Hence the corresponding combing wheel 7 acting upon the other edge of the sheet which is supposedly in the rear, is caused to catch up, and the top sheet is therefore properly presented to the front gages. As pointed out in the above mentioned Dexter application, it may happen in machines of this character that for some reason or other, the movement of the top sheet may be retarded to such an extent that the forward edge thereof does not arrive at the front gages within the periodic interval allowed by the cam 10, during which the combing wheels 7 are acting upon said sheet. In the said Dexter application, mechanism is disclosed for reducing the pressure on the tail drag for the purpose of facilitating the movement of the top sheet. According to the present application, similar mechanism is provided which effects the same result in an improved manner, the pressure existing upon the tail drag being reduced to normal again after each variation, prior to the beginning of the next sheet combing operation. Thus by referring to Fig. 1, it will be seen that the roller 9 is approximately midway of its inner run on the cam 10. Also keyed to the cam shaft 11 is a cam 28 which, according to the showing of Fig. 1, is about to engage a cam roller 29 carried by a cam arm 30, which is pivoted on a stud 31. The displaceable element in the form of a link 32 has its forward end pivotally connected at 33 with the lower end of the cam arm 30. The rear end of the link 32 is provided with a shoulder for engaging a laterally projecting pin

or lug 34 mounted on a lever 35, which is pivoted at 36. The upper end of said lever is pivotally connected at 37 to one end of a cam bar 38, the other end of said cam bar being pivoted at 39 to a radial arm 40 journaled upon a short shaft 41. A pressure foot 42 which constitutes the pressure-applying member of the tail drag, is pivoted at 43 to the lower end of a spring rod 44, said spring rod being slidably mounted in spaced bearing lugs 45 which are mounted on a block 46, said block 46 being slidably adjustable along a suitable frame or support 47. Supporting bar 47 is pivotally mounted (preferably at one end) upon a stud 47' which is threaded into the bracket 72. An arcuate slot 2' in the bracket 72 permits the passage of a bolt 73 which serves to clamp the supporting bar 47 to the bracket 72 in whatever position to which it may be adjusted. As shown best in Fig. 2, the spring rod 44 carries a block 48 intermediately of the bearing lugs 45, said block 48 serving to mount a journal pin of a cam roller 49 which is adapted to be engaged by the cam bar 38 when it is raised in the manner to be pointed out. Mounted on the spring rod 44 is a spring 50 which is interposed between the lower end of a slide block 46 and an adjustable abutment 51 which is threaded to the rod 44 for adjusting the tension of the spring 50.

The construction and arrangement of these parts are such that whenever the cam 28 engages the cam roller 29, the link 32 (provided it has not been displaced in the manner to be referred to) transmits power to the cam rod 38, causing said cam bar to move upwardly to engage the cam roller 49 and thus lifting the spring rod 44 against the tension of spring 50 and removing pressure foot 42 from the top sheet of the pile. In order to provide simple and efficient means for preventing this action when the parts are operating normally and the sheets are being fed regularly, a device for elevating the link 32 so that its shoulder will not engage the pin 34, must be provided. This may be accomplished by connecting said link 32 to the lever arm 5 by means of a spring 52 or other suitable connection, whereby when the lever arm 5 is lifted by the cam 18 under the control of the sheet actuated pendulum 22, the link 32 will be lifted therewith, thus preventing the pressure reducing action. If preferred, a cam finger 53 may be keyed to the shaft 15 as shown in Fig. 3, said finger being adapted to engage a lug 54 on the link 32 whenever the combing wheel 7 is raised.

By an inspection of Fig. 1, it will be seen that the cam 10 has still considerable angular distance to travel before it operates the cam roller 9, whereas the cam 28 is in a position in which it is about to throw the cam arm 30 to the left to effect a reduction of

pressure on the tail drag. This angle of travel of the cam 10 allows sufficient time in most instances to get the top sheet down to the front gages under the reduced pressure on the tail drag. A tail clamp 55 (see Fig. 1) which is carried by a spring rod 56, is slidably mounted in spaced bearing lugs 57 carried by a slide 58 which is adjustable on the bar or side frame 47. Mounted on the rod 56 intermediately of the bearing lugs 57 is a block 59 which carries a cam roller 60 which is suitably disposed to be engaged by a cam bar 61 in raised position indicated on the drawings. One end of the cam bar 61 is pivotally connected at 62 with a radial arm 63. The other end of said cam bar is pivotally connected at 64 with one arm of the lever 65, said lever being pivoted on the short shaft 36 and having its other arm 20 pivotally connected at 66 with one end of the link 67. The other end of the link 67 is pivotally connected to a cam arm 68 which depends from the short shaft 31 and carries a cam roller 69 which runs on a cam 70, said 25 arm being shown in Fig. 1 having its outer run in contact with the roller 69, thus causing the tail clamp 55 to be raised. An adjustable abutment 70' which is threaded to the rod 56 serves to adjust the tension of the spring 71 under which the tail clamp is 30 pressed to the pile.

Referring now to Fig. 2, the rearwardly projecting end of a bracket frame 72 is adjustably secured to and serves to support the bar or frame 47 by means of the stud 73 which is held in position by a nut 74. The drop roller shaft 75 is provided with the forwardly extending arm 76 carrying a cam roller 77 which is operated by the drop 40 roller cam (not shown) on cam shaft 11. A lever arm 80 carries the drop roller 81. Keyed to the shaft 75 is also a stop finger 82 which when the pendulum is in elevated position permitting the top sheet to be fed off and the drop roller in lowered position to effect this feeding off, is interposed in the path of the radial arm 19 within which one end of the pendulum shaft 20 is journaled. This positively prevents the pendulum 22 being dropped onto a sheet which is being fed from the pile, which might cause 50 injury to the sheet.

The operation of the mechanism hereinabove described briefly considered is as follows: By an inspection of Fig. 1, it will be evident that whenever the outer run of the cam 10 is in engagement with the cam roller 9, the combing wheel 7 on that side of the machine will be positively retained in elevated position. As soon as the cam roller 9 reaches the inner run of the cam 10, said combing wheel will be permitted to operate upon the bank of sheets until said roller again travels to the outer run of said cam 10, provided that the top sheet does not in

the meantime actuate the pendulum 22 and cause the combing wheel to be lifted by means of the oscillatory shaft 15, segmental ratchet 16, pawl 21 and cam 18, which acts on the cam roller 23. During the normal 70 working of the sheet combing instrumentalities, if the sheets are presented at suitable intervals, the pressure exerted by the pressure foot 42 will remain substantially constant under the resilient action of spring 50. 75 Under these conditions, each of the combing wheels 7 will be raised at such intervals relatively to the timing of the cams 28, that the link 32 will be raised before said cam 28 imparts a rearward movement thereto, thus 80 preventing the upward movement of the cam bar 38 which would engage the cam roller 49 and lift the pressure foot 42 from the pile. If, on the other hand, the duration of the period of activity of the combing 85 wheel is prolonged by the retardation of the top sheet which would prevent the forward edge thereof being brought to the front gages prior to the periodic lift of said combing wheel 7, the cam 28 will engage the cam 90 roller 29 and cause the link 32 to be driven rearwardly before it is raised, thus causing the cam bar 38 to be lifted and removing the pressure foot 42 from the pile. In consequence, the movement of the top sheet will 95

be facilitated to bring it against the front gages prior to the regular periodic lift of the combing wheel 7. If, again, the movement of the top sheet should be delayed until after the cam 28 had caused a reduction of pressure on the tail drag, in the manner indicated and the top sheet had been thereby moved to the front gages prior to the regular periodic action of cam 10, on the combing wheel 7, the pendulum 22 would be 100 displaced along with the pawl 21 and immediately the combing wheel 7 would be lifted, as well as the driving link 32. The upward movement of the driving link 32 would immediately release the cam bar 38, permitting the cam roller 49 to drop and automatically returning the tail drag to normal pressure, all of these operations being completed within a single cycle of the paper feeding operations. As will appear upon an inspection of Fig. 1, the cam 70 operates upon the cam roller 69 to elevate the tail clamp 55 approximately throughout the period of time during which the combing wheel 7 is in lowered position, when the sheet registry is delayed until the regular periodic operation of cam 10.

I claim:

1. In a feeding machine, a sheet-feeding instrumentalities movable into and out of engagement with the top sheet of a pile, sheet-actuated means, for terminating the action of said sheet-feeding instrumentalities, a tail drag capable of exerting different pressures on a pile of sheets, means including detach- 130

ably connected elements for transmitting power to said tail drag to vary the pressure exerted thereby, and means under the control of said sheet-actuated means for disconnecting said elements.

2. In a feeding machine, a sheet-feeding instrumentality movable into and out of engagement with the top sheet of a pile, sheet-actuated means for determining the duration of the period of activity of said sheet-feeding instrumentality, means including detachably connected elements for exerting more or less pressure on said sheet to shorten or lengthen the period during which said sheet-feeding instrumentality is active, and means operated by the movement of said instrumentality away from said top sheet for disconnecting said elements.

3. In a feeding machine, a sheet-feeding instrumentality periodically engaging the top sheet of a pile, sheet-actuated means for determining the duration of the period of activity of said sheet-feeding instrumentality, means for exerting more or less pressure on said sheet to shorten or lengthen the period during which said sheet-feeding instrumentality is active, said pressure exerting means including detachably connected elements, and means subject to the sheet-actuated means for disconnecting said elements.

4. In a sheet feeding machine, an automatic sheet feeding device capable of periodic intervals of activity, a tail drag operating upon the rear of a bank of sheets, a power shaft, a mechanical train connecting said power shaft with said tail drag, said train including a pivotally mounted link movable into and out of power transmitting position in said train, sheet actuated means for regulating the intervals of activity of said sheet feeding device, and means depending on the action of said sheet actuated means for moving said link into and out of power transmitting position.

5. In a sheet feeding machine, an automatic sheet feeding device capable of periodic intervals of activity, a tail drag operating upon the rear of a bank of sheets, a power shaft, a mechanical train connecting said power shaft with said tail drag, said train including a pivotally mounted link movable into and out of power transmitting position in said train, sheet actuated means for regulating the intervals of activity of said sheet feeding device, and moving means depending on the action of said sheet actuated means for moving said link out of power transmitting position, under a normal duration of said period of activity of the sheet-feeding device, said link remaining in power-transmitting position under a prolonged period of activity of the same.

6. In a sheet-feeding machine, a sheet-combing instrumentality, movable into and

out of engagement with the top sheet of a pile, sheet-actuated means for controlling the period of activity of said sheet-combing instrumentality, variable pressure means for retarding the movement of a sheet under the action of said sheet-combing instrumentality, a positively driven element, non-yieldable means for transmitting power from said positively driven element to said variable pressure means, said non-yieldable means including detachably connected elements, and means under the control of said sheet-combing instrumentality for disconnecting said detachably connected elements to render said power-transmitting means inoperative.

7. In a sheet-feeding machine, a sheet-combing instrumentality movable into and out of engagement with the top sheet of a pile, sheet-actuated means for controlling the period of activity of said sheet-combing instrumentality, variable pressure means for retarding the movement of a sheet under the action of said sheet-combing instrumentality, a positively driven element, non-yieldable means for transmitting power from said positively driven element to said variable pressure means, said non-yieldable means including detachably connected elements, and means under the control of the rising movements of said sheet-combing instrumentality for disconnecting said detachably connected elements to render said power-transmitting means inoperative.

8. In a sheet-feeding machine, a sheet-combing instrumentality movable into and out of engagement with the top sheet of a pile, sheet-actuated means for controlling the period of activity of said sheet-combing instrumentality, variable pressure means for retarding the movement of a sheet under the action of said sheet-combing instrumentality, a positively driven element, non-yieldable means for transmitting power from said positively driven element to said variable pressure means, said non-yieldable means including detachably connected elements, and means depending upon said sheet-actuated means for disconnecting said detachably connected elements.

9. In a feeding machine, a sheet-combing instrumentality movable into and out of engagement with the top sheet of a pile, sheet-actuated means for terminating the action of said sheet-combing instrumentality, a tail drag capable of exerting different pressures on a pile of sheets, means under the control of said sheet-actuated means for modifying the pressure exerted by said tail drag, said pressure-modifying means including a power-transmitting bar, normally inoperative means for driving said bar, and means under the control of said sheet-actuated means for rendering said driving means inoperative, said tail drag comprising a pres-

sure shoe, yieldable means for normally pressing said shoe against the top sheet of a pile, and means connected to said shoe and adapted to be engaged by said power transmitting bar for lifting said shoe from the pile at each operation of said power transmitting bar.

10. In a feeding machine, a sheet-feeding instrumentality movable into and out of engagement with the top sheet of a pile, sheet-actuated means for determining the duration of the period of activity of said sheet-feeding instrumentality, a pressure foot for exerting more or less pressure on said sheet 10 to shorten or lengthen the period during which said sheet-feeding instrumentality is active, and variable pressure means comprising yieldable means for pressing said pressure foot against said top sheet and 20 means for lifting said pressure foot out of engagement with said top sheet against the pressure of said yieldable means, said pressing means comprising a fixed abutment, a rod slidably mounted therein, an abutment 25 mounted on said rod, and a spring mounted on said rod between said abutments.

11. In a feeding machine, a sheet-feeding instrumentality movable into and out of engagement with the top sheet of a pile, sheet 30 actuated means for determining the duration of the period of activity of said sheet feeding instrumentality, a pressure foot for exerting more or less pressure on said top sheet to shorten or lengthen the period during 35 in which said sheet feeding instrumentality is active, a fixed abutment, a rod slidably mounted in said abutment, an abutment carried by said rod, a spring mounted on said rod between said abutments, a cam roller 40 mounted on said rod, and means under the control of said sheet-actuated means for displacing said cam roller.

12. In a feeding machine, a sheet-feeding instrumentality movable into and out of engagement with the top sheet of a pile, sheet-actuated means for determining the duration of the period of activity of said sheet feeding instrumentality, a pressure foot for exerting more or less pressure on said top 45 sheet to shorten or lengthen the period during which said sheet feeding instrumentality is active, a fixed abutment, a rod slidably mounted in said abutment, an abutment carried by said rod, a spring mounted on said 50 rod between said abutments, a cam roller mounted on said rod, and means under the control of said sheet actuated means for displacing said cam roller, the last said means being operable only when said sheet-feeding instrumentality is in engagement with said top sheet.

13. In a feeding machine, a sheet-feeding instrumentality movable into and out of engagement with the top sheet of a pile, sheet-actuated means for determining the duration 55 of the period of activity of said sheet

of the period of activity of said sheet feeding instrumentality, a pressure foot for exerting more or less pressure on said top sheet to shorten or lengthen the period during which said sheet feeding instrumentality is active, a fixed abutment, a rod slidably mounted in said abutment, an abutment carried by said rod, a spring mounted on said rod between said abutments, a cam roller mounted on said rod, and means under the control of said sheet actuated means for displacing said cam roller, the last said means including a cam bar for operating said cam roller, a link movable into and out of position to drive said cam bar, and means for displacing said link to render the cam bar 70 inoperative.

14. In a feeding machine, a sheet-feeding instrumentality movable into and out of engagement with the top sheet of a pile, sheet-actuated means for determining the duration of the period of activity of said sheet feeding instrumentality, a pressure foot for exerting more or less pressure on said top sheet to shorten or lengthen the 80 period during which said sheet feeding instrumentality is active, a fixed abutment, a rod slidably mounted in said abutment, an abutment carried by said rod, a spring mounted on said rod, between said abutments, a cam roller mounted on said rod, a power-driven link movable into and out of position to drive said cam bar, and means for moving said link out of power-transmitting 90 position when said sheet feeding instrumentality is removed from the pile.

15. In a feeding machine, a sheet-feeding instrumentality movable into and out of engagement with the top sheet of a pile, sheet-actuated means for determining the duration of the period of activity of said sheet feeding instrumentality, a pressure foot for exerting more or less pressure on said top sheet to shorten or lengthen the 100 period during which said sheet feeding instrumentality is active, a fixed abutment, a rod slidably mounted in said abutment, an abutment carried by said rod, a spring mounted on said rod between said abutments, a cam roller mounted on said rod, a power-driven link movable into and out of position to drive said cam bar, and means for displacing said cam roller, the last said means including a cam bar for operating said cam roller, a link 110 movable into and out of position to drive said cam bar, and means for displacing said link to render the cam bar inoperative, said link displacing means being controlled by said sheet-actuated means.

16. In a feeding machine, a sheet-feeding instrumentality movable into and out of engagement with the top sheet of a pile, sheet-actuated means for determining the duration of the period of activity of said sheet 120

- 6 feeding instrumentality, a pressure foot for exerting more or less pressure on said top sheet to shorten or lengthen the period during which said sheet feeding instrumentality is active, a fixed abutment, a rod slidably mounted in said abutment, an abutment carried by said rod, a spring mounted on said rod between said abutments, a cam roller mounted on said rod, and means under the control of said sheet-actuated means for displacing said cam roller, the last said means including a cam bar for operating said cam roller, a power driven cam shaft, a cam arm operated thereby, and a link detachably connected to said cam bar and driven by said cam arm.
17. In a feeding machine, a sheet-feeding instrumentality movable into and out of engagement with the top sheet of a pile, sheet-actuated means for determining the duration of the period of activity of said sheet feeding instrumentality, a pressure foot for exerting more or less pressure on said top sheet to shorten or lengthen the period during which said sheet feeding instrumentality is active, a fixed abutment, a rod slidably mounted in said abutment, an abutment carried by said rod, a spring mounted on said rod between said abutments, a cam roller mounted on said rod, and means under the control of said sheet-actuated means for displacing said cam roller, the last said means including a cam bar for operating said cam roller, and a power driven link detachably connected to said cam bar.
18. In a feeding machine, a sheet combing instrumentality movable into and out of engagement with the top sheet of a pile, sheet-actuated means for determining the duration of the period of activity of said sheet combing instrumentality, a tail drag normally pressing the pile of sheets, means for reducing the pressure exerted by said tail drag to regulate the duration of the period of comb, said combing instrumentality being provided with sheet-actuated means for controlling the movement of said instrumentality away from the pile of sheets, said pressure reducing means comprising a cam operated arm, a link pivoted thereto, a lever provided with a lateral projection, said link having a free end provided with a shoulder for engaging said projection, a cam roller mounted on said tail drag, a cam bar operating on said roller, said cam bar being connected to said lever, and means under the control of said sheet actuated means for moving said link into and out of position in which said shoulder engages said projection.
19. In a paper feeding machine, a sheet combing device, means for moving said device into and out of engagement with the top sheet of a pile, a tail drag subject to variable pressure, means for varying the pressure of said tail drag, said means being
- 5 normally inoperative under a predetermined period of activity of said sheet-combing device and adapted to become operative when the period of activity changes, a tail grip provided with a spring rod, a cam roller 70 mounted thereon and a spring surrounding said rod, a cam bar co-operating with said roller, and means for operating said cam bar.
20. In a paper feeding machine, sheet-actuated tripping mechanism for controlling the register of a sheet, said mechanism including a pendulum adapted to be engaged by a sheet, means for moving said pendulum out of the path of said sheet subsequent to the registry of the sheet, a drop roller, a shaft for moving said drop roller into and out of sheet engaging position, and means operated by the movement of said shaft which corresponds to the drop of said drop roller, for holding said pendulum out of the path of said sheet during the activity of said drop roller.
21. In a paper feeding machine, a sheet-feeding device, a tripping mechanism for said device having a pendulum depending in 90 the path of a sheet, said pendulum being movable by said sheet to control the termination of the period of activity of said feeding device, means for moving said pendulum out of the path of said sheet, a drop roller 95 shaft, a drop roller mounted thereon and a finger carried by said drop roller shaft, the movement of said shaft being adapted to move said finger into and out of position blocking the return of the pendulum into 100 the path of said sheet.
22. In a paper feeding machine, a paper combing device, means for moving said device into and out of engagement with the paper, a tail drag subject to variable pressure, and means for varying the pressure of said tail drag, said means being normally inoperative under a predetermined period of activity of said sheet combing device and adapted to become operative under a change 110 in said period of activity, said pressure varying means being adapted to reestablish normal conditions corresponding to said predetermined period of activity within the same 115 combing operation.
23. In a paper feeding machine, a sheet combing device, means for moving said device into and out of engagement with the top sheet of a pile, sheet-actuated means for controlling the operation of said device moving means, a tail drag exerting a yieldable pressure on a pile of sheets, a cam roller carried by said tail drag, a cam bar for engaging said roller to elevate said tail drag, and means for moving said cam bar, said 120 cam bar being adapted to release said cam roller automatically when said cam bar moving means ceases to operate thereon.
24. In a paper feeding machine, the combination with a support, of a slide 125

on said support, said slide being provided with spaced bearing lugs, a rod reciprocably mounted in said bearing lugs, a block secured to said rod intermediately of said bearing lugs, a cam roller journaled on said block, a cam for operating on said cam roller, a pressure exerting element carried by said rod, and means yieldably depressing

said rod, said support being pivotally mounted and provided with means for clamping it in any position to which it may be adjusted.
